PLASTIC HANDBAG

Carolyn N. Munn, New York, N. Y.

Application December 4, 1951, Serial No. 17,599

Term of patent 14 years

(Cl. D87—3)

To all whom it may concern:

Be it known that I, Carolyn N. Munn, a citizen of the United States of America and a resident of New York, county and State of New York, have invented a new, original, and ornamental Design for a Plastic Handbag, of which the following is a specification, reference being had to the accompanying drawings, forming part thereof, in which:

Fig. 1 is a perspective view of my design for a plastic handbag;

Fig. 2 is a front view of my design for a handbag; and

Fig. 3 is a view in section taken on line 3—3 of Fig. 1 and looking in the direction of the arrows.

I claim:

The ornamental design for a plastic handbag, as shown.

CAROLYN N. MUNN.
